TOWEL CABINET

Ole J. Flack, Minneapolis, Minn., assignor to
Steiner Sales Company, Salt Lake City, Utah,
a Corporation of Utah

Application October 29, 1930. Serial No. 491,953

27 Claims. (Cl. 312—38)

In towel dispensing cabinets, of the so-called floor type having means for winding up the soiled web as fast as the clean portion is dispensed, the person loading or putting the clean towel into the cabinet should provide a loop or length of towel sufficient to enable the subsequent user to draw it out of the cabinet to a position convenient for use. The attendants or janitors in office buildings and other places are carefully instructed to load the cabinets properly and pull out a sufficient length of clean towel to form the desired loop before leaving the cabinets. Frequently, however, these instructions, through carelessness or inattention, are forgotten and the clean towel will be placed in the cabinet and the take up mechanism connected with the loose end without any provision being made for drawing a loop of sufficient length out of the cabinet to enable a user to conveniently wipe the hands or face. Sometimes the towel will be put in the cabinet with the loose end drawn so tight that a person can scarcely make use of the towel web and thereby the usefulness of the cabinet is practically destroyed. The success of a cabinet as a means to supply the public with clean towel is, therefore, as now handled, practically dependent upon the memory and care of the person entrusted with the towel loading operation.

The primary object, therefore, of my invention is to provide a towel cabinet having means whereby when a supply of clean towel is put into the cabinet, wiping lengths may be dispensed upon release of the control locking mechanism, but the loose end of the towel will not be gathered or wound up within the cabinet until a loop of predetermined length is formed between the dispensing and winding mechanism. The successful use of the cabinet, therefore, is not dependent upon the care or memory of the person loading it with clean toweling. The desired length of loop may be formed by the attendant after loading the cabinet or it may be effected by the user who after manipulating the locking device may draw out the web in successive lengths until a loop of predetermined length has been formed, and then, and only then, will the take up or winding operation automatically begin.

A further object is to provide a towel cabinet in which provision is made for easily and quickly winding up the loose end on the winding roll when the clean supply is exhausted.

A further object is to provide a cabinet in which provision is made for the convenient removal from the cabinet of the instrumentalities by

which the delivery or feed of the clean towel and the wind-up of the soiled towel is effected.

Other objects of the invention will appear from the following detailed description.

In the accompanying drawings forming part 60 of this specification

Figure 1 is a vertical sectional view through a towel cabinet embodying my invention in its loading position, the lower portion being broken away;

Figure 2 is a similar view showing the cabinet in condition for use in forming a loop of the desired length in the towel web;

Figure 3 is also a vertical sectional view showing the operating parts of the cabinet in condition to vend the length of clean towel and wind up a corresponding length of soiled towel;

Figure 4 is a vertical sectional view showing the door in the top of the cabinet raised preparatory to the removal of the soiled towel roll;

Figure 5 is a detail sectional view showing in detail the mechanism which controls the movement of the soiled towel roll;

Figure 6 is a front view of the same;

Figure 7 is a view of the upper portion of the 80 cabinet partially in section showing the manner of supporting the removable frame section;

Figure 8 is a sectional view showing a modified form of the mechanism which controls the engagement of the soiled towel roll with the frictional take-up or winding roll;

Figure 9 is a detail view of a part of Figure 8 showing the position the control mechanism assumes when the door in the cabinet is open to remove the towel roll;

Figure 10 is a view corresponding to Figure 8 showing another modification of the control mechanism;

Figure 11 is a detail view similar to Figure 9 showing the position assumed by the parts when the towel roll is removed from the cabinet.

In the drawings 2 represents the side walls of the cabinet having a closed back 3 and a lower front panel 4 above which is an opening 5 through which access may be had to the clean towel. This cabinet is preferably constructed of sheet metal but any suitable material may be used. In the rear of the opening 5 in the cabinet is a carrier 6 adapted to receive a roll of clean towel 7. This carrier preferably has a curved bottom 105 whereon the roll of clean towel is seated and is free to roll back and forth therein as the clean towel is unwound. A pivot 7' at the front of the cabinet supports the carrier and a panel 8 forms an upward continuation of the curved bottom 110

of the carrier and closes the upper portion of the opening 5 when the cabinet is in use. A space 9 is provided between the carrier and an anti-friction roll 10 that is mounted in the lower portion 5 of the opening 5. Through this space the attendant may insert his hand and stretch the web of the towel from the clean roll to the soiled towel roll in the rear of the cabinet. Panel 8 has a concave area 11 for convenience of the user 10 in grasping the web of towel. A door 12 is provided for the open top of the cabinet supported by brackets 13 which are pivoted at 14 to the rear wall of the cabinet. This door is curved to correspond to the curvature of the top of the 15 cabinet and when it is closed and secured by a suitable locking means 15, its lower edge, as shown plainly in Figure 2 will depend below the upper edge of the panel 8 and it will not be possible to pull the panel forward and expose the 20 supply of clean towel until the door 12 is raised. When this has been done the clean towel carrier may be tilted on its pivot as indicated by dotted lines in Figure 4 and access may then be had to the carrier as when it is desired to insert a clean 25 roll therein or to have access to the roll for any purpose. I prefer to provide means for normally holding the door 12 in its raised or open position consisting of latches 12^a pivoted at one end to the brackets 13 and having longitudinal slots 12^b 30 provided with off sets or notches to receive pins 12^c mounted on the side walls of the cabinet, these latches when the door is raised serving to hold it in its open position as usual in devices of this kind.

35 A frame is removably mounted in the upper portion of the cabinet and comprises side plates 16 supported on a rod 17 which passes through said plates and has its ends, one being shown in Figure 7, fitting within a hollow supporting stud 18 and held therein by a cotter pin 19 which passes through said rod, the walls of the stud and a spacing collar 20. The other end of the rod 17, not shown, is supported in a similar manner. The rod has shoulders 17' thereon to engage and hold the plates 16 in their proper position with respect to the side walls of the cabinet. The lower edges of the plates 16 have notches 22 therein to receive a rod 23, the ends of which are mounted in the side walls of the cabinet. This rod, while allowing the plates 16 and the mechanism carried thereby to be conveniently lifted out of the cabinet, when disconnected from the supporting studs 18, prevents any premature forward or backward movement 50 of the lower portion of the section. A guard plate 24 is secured to the plates 16 and extends inwardly and downwardly therefrom, terminating near the inner edge of the curved bottom of the clean towel carrier and provided with a horizontal flange 25 with which the web of towel contacts in passing to the soiled towel roll. The forward edges of the plates 16 are provided with stops 26 with which the panel 8 contacts when it is moved to its closed position.

65 The clean towel feeding instrumentality, in this case the friction roll 27, is mounted in bearings in the plates 16 near the opening in the front of the cabinet and has a driving connection 28 with the corresponding friction take-up roll 29 also mounted in said plates towards the rear of the cabinet. The plates 16 have guide slots 30 for the spindle of a pinch roll 31 that is adapted to ride on the feed roll 27 and has the function of pressing the clean towel web against the feed roll sufficiently to cause revolution of

the roll when the towel is drawn out of the cabinet. The lower portion of the slots 30 are inclined so that the pull on the towel web that is stretched between the feed roll and the pinch roll will draw the rolls together and create the desired frictional contact of the web with the feed roll 27. The upper portion of the slots 30 has an off-set 32 in which the spindle of the pinch roll 31 is supported when the cabinet is not in use and when the attendant wishes to stretch the clean web between the pinch roll and the feed roll preparatory to drawing it out of the cabinet. This off-set 32 is in close proximity to a clip 33 that is mounted on the door 12 so that when the door is closed the pinch roll will be automatically dislodged from the off-set 32 to drop by gravity to its working position upon the feed roll 27.

When the pinch roll has been dislodged by the closing of the cover to assume the position shown in Figure 2, the pull of the user on the exposed web of the towel will revolve the feed roll 27 and unwind the clean towel from the roll 7. It is of course desirable that a loop of the clean web of sufficient length be provided so that the user standing in front of the cabinet can draw the web out through the opening a sufficient distance for convenient use, while at the same time a length of the soiled towel is gathered into or wound up within the cabinet, corresponding substantially to the length of the clean web that is pulled out of the cabinet by the user. The attendant in loading the cabinet makes provision for this desired length of the towel loop so that each user may draw out of the cabinet a predetermined length of the towel each time it is operated. This loop regulating or controlling feature of the cabinet forms the principal subject matter of my present invention.

Referring now to the drawings, the plate 16 on each side of the cabinet has a slot 34 therein extending from the upper edge of each plate downwardly to a point near the surface of the take-up feed roll 29. Only one plate and slot 120 is shown in the drawings, but it will be understood that the other side of the cabinet is equipped in a similar manner. The spindle of the soiled towel roll 35 is adapted to slide in these slots and intermediate the upper and lower 125 end of each slot is an off-set or enlargement 36 formed in the plate 16. A plate 37 is provided on each side of the cabinet and adapted to move across the slot 34 and temporarily prevent the downward movement of the roll 35 therein. This plate 37 is pivotally supported at its lower end at 38 on a bar 39 which is provided near the pivot 38 with a longitudinal slot 40. The upper end of each bar 37 has a projection 41 formed thereon which merges into a recess or depression 42 formed in the upper edge of the plate. This depression, one in each plate, is adapted to receive the spindle of the towel roll and hold it in place while the person removing the soiled towel from the cabinet turns the towel roll to wind up the loose end of the towel. The plate 37 is also provided with a slot 43, the lower portion of which is enlarged to form an opening 44. A pin 45 is mounted in the side wall of the cabinet and passes through the opening 44 and is provided with washer-like plates 46, secured thereto as shown in Figure 6, to guide the forward and backward movement of the plate 37. This plate being connected at its lower end to the sliding bar 39, evidently will have a longi-

tudinal as well as a forward and backward movement. The enlargement of the slot 43 at the bottom allows for this movement and permits the plate to assume its proper position in 5 the operation of the soiled towel roll control mechanism.

A stationary guide 47 is mounted on the rear wall of the cabinet and projects inwardly therefrom to a point near the guard plate 24, the towel web contacting with this guide as the web is stretched upwardly to the soiled towel roll. A movable guide 48 is pivoted at 49 on the rear wall of the cabinet above the stationary guide and is adapted to swing downwardly to a horizontal position through its pivotal connection with a pin 50 which passes through the slot 40 in the bar 39. A link 51 connects the pin 50 with an arm 52 on the bracket 13 whereby movement of the door carried by the bracket 13 will impart a 20 corresponding movement to the bar 39 and the mechanism connected therewith.

The lower end of the bar 39 is pivotally connected on each side of the cabinet to bars 53 pivoted at 54 to the rear wall of the cabinet and supporting a roll member 55 forming therewith a pivoted take-up yoke. A fixed yoke 56 is mounted on the rear wall of the cabinet adjacent the pivot 54 and projects inwardly therefrom towards the front of the cabinet and has the function of holding the towel web out towards the front wall of the cabinet and form an angle in the towel loop providing several inches more for the user. The bars of this fixed yoke are of less length than the bars 53 so that the roll 55 may drop down 35 to its substantially vertical position below the fixed yoke, as shown in Figure 3, or be raised to an inclined position above said yoke. In loading the cabinet the web of towel is passed under the roll 55 and through the connection of this roll with the bars 39 and the plates 37 a predetermined length of towel may be drawn out of the cabinet before the soiled towel roll is allowed to assume its operating position.

Turning now to Figures 1 and 2, the loading 45 and loading condition of the cabinet, we find with the cover raised that both the friction rolls 27 and 29 are idle. This allows for the convenient insertion of the clean web into the cabinet, the roll being inserted into the carrier and the 50 loose web carrier upwardly over the pinch roll 31 and from thence downwardly under the roll 55 to the roll 35 which is inserted through a loop in the end of the towel. The attendant will then close the door in the top of the cabinet and in so doing the pinch roll will be automatically dislodged and will drop down upon the friction roll 27 and the panel 8 being locked upon closing of the door, further delivery of the towel must be effected by pull on the clean web. This will have the effect of turning the rolls 27 and 29. No winding action, however, will take place as the soiled towel roll is temporarily held out of engagement with the roll 29 and the attendant may draw out the web of clean towel, it being necessary of course to manipulate the locking device by means of which the feed of the clean towel is controlled. The locking device used in this cabinet corresponds substantially to the one shown in Frank G. Steiner Patent 1,724,229, August 13, 1929, and comprises briefly a sliding bolt 57 adapted to engage a stop 57^a and a slide 57^b in the path of a pushbutton, not shown, for moving the sliding bolt to its release position, the slide 70 being controlled by a projecting finger 57^c thereon which engages the periphery of a cam 57^d.

By means of this locking device the delivery roll is normally locked but may be released to make a single revolution and permit the delivery of a predetermined length of clean towel. As the feed roll is operated and the web of towel pulled out 80 of the cabinet, the loop formed between the feed roll and the soiled towel roll increases in length and the yoke roll 55 may drop by gravity to a lower position with each operation and as this roll continues to drop, a corresponding movement will be imparted to the bar 39 and as the roll 55 and the bar 39 descend, the plate 37 will also slide downwardly on its pivot to the position indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

85 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

90 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

95 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

100 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

105 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

110 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

115 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

120 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

125 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

130 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

135 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

140 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

145 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

150 indicated by full lines in Figure 3 and when this takes place the projection 41 will be opposite the enlargement 36 in the slot and the soiled towel roll will be free to drop by gravity to the bottom of the slot and engage the friction roll 29. At that time the roll 55 will have reached the limit of its downward movement, as shown in Figure 3 and a loop of the desired length will have been

In Figure 10, another modification is shown which consists in a bar 67 pivoted at its lower end to the bar 39 and having an angularly arranged slot 68 in its upper end to receive a pin 69 mounted on a latch 70 that is pivoted at 71 on the plate 16. The working position of this latch is illustrated in Figure 11, where it is shown extending across the slot and supporting the spindle of the soiled towel roll. The latch may be swung on its pivot as indicated by dotted lines in Figure 11 to allow the convenient removal of the towel roll from the slots which guide it to its working position on the take-up roll.

The operation of the cabinet is as follows. Referring to Figure 1 the cabinet is shown with the soiled towel removed, a clean roll placed therein and the loose end of the web drawn out and passed under the carrier and the pivoted yoke to the soiled towel roll. So far, the towel delivering and winding mechanism will be inactive. As soon, however, as the cover in the top of the cabinet is closed, pull upon the towel web will revolve the feed roll and with each revolution, a predetermined length of web will be fed out of the cabinet where it can be reached conveniently by the user. The loose end passed under the carrier through the opening 9 on its way to the towel roll will be engaged by the pivoted yoke member, which until the door is closed, will occupy the raised position shown in Figure 1. As soon, however, as the door is closed the yoke member will drop slightly through the lowering of the bars 39 and will rest upon the towel loop, exerting a downward pull thereon. The soiled towel roll, however, will be held in the upper part of its guides as shown in Figures 1 and 2 and no winding or gathering of the soiled towel can take place while the roll is in this position. The attendant before leaving the cabinet should operate the delivery roll a sufficient number of times to form a loop of the desired length and allow the pivoted yoke member to drop and release the towel roll. If the attendant, through inattention, or forgetfulness, should fail to do this, the first user will add somewhat to the length of the loop as he operates the delivery roll and other users will do the same until the loop is of such length that the pivoted yoke member may drop to the position shown in Figure 3 when the plates supporting the towel roll will slide downward and allow the spindle of the towel roll to slide between projection 41 on said plates and drop into contact with the take up roll beneath. Revolution of the soiled towel roll will then begin, actuated through its frictional contact with the take up roll and from that time; with each delivery of a wiping length of clean towel, a corresponding length of soiled towel will be wound up on the towel roll and this operation may continue until the supply of clean towel is exhausted. At that time most of the soiled towel will be wound on the towel roll and the attendant opening the door as shown in Figure 4 may raise the roll, place its spindle in the recesses 42 in the upper ends of the supporting plates and then by revolving the towel roll, he can easily and quickly wind up the loose end to form a compact bundle. At that time the carrier may be tilted outwardly as indicated by dotted lines in Figure 4 to receive a roll of clean towel and the attendant may then stretch the loose end of this clean towel from the delivery roll down in front of the carrier through the opening below the carrier and beneath the pivoted yoke member up to the soiled

towel roll, the spindle of which is supported on the upper ends of the tilting plates which will prevent the engagement of the towel roll with the take-up roll until a loop of desired length has been formed.

In various ways the details of construction herein shown and described may be modified and still be within the scope of my invention.

I claim as my invention:

1. In a towel cabinet, a clean towel delivering means adapted to dispense a supply of clean towel, a soiled towel winding means for taking up the soiled towel and mechanism whereby said winding means is prevented from operatively engaging the soiled towel and is thereby rendered temporarily inoperative to wind up the soiled towel until a loop of the desired length has been formed between said delivering and winding means.

2. A clean towel delivering means adapted to dispense a length of clean towel, a soiled towel roll for simultaneously winding up the soiled towel, a friction take-up roll for driving contact with said towel roll, and means normally preventing contact of said towel roll with said take-up roll until a predetermined length of clean towel has been delivered.

3. A clean towel delivering means for dispensing lengths of clean towel, a soiled towel roll for winding up the soiled towel, a take-up roll having a friction surface for contact with the towel on said roll, a door and mechanism connected therewith whereby contact of said towel roll with said take-up roll is permitted only when a predetermined length of towel loop has been formed between said delivering means and said take-up roll.

4. In a towel cabinet, a clean towel delivering means, a frictional take-up roll, a roll on which the soiled towel is wound having a movement toward and from said take-up roll, pivoted plates normally supporting the roll for the soiled towel and preventing its contact with said friction roll, and a door for said cabinet having means connecting it with said plates, whereby the movement of said plates to release said soiled towel roll is prevented until said door is closed.

5. In a towel cabinet, means for delivering clean towel, a roll for the soiled towel and means operating synchronously with said delivering means to wind up the soiled towel on said roll, a door for the top of said cabinet, means adapted to support the soiled towel roll and prevent it temporarily from contacting with said winding means, bars pivotally connected with said supporting means and having a vertical sliding movement, links pivotally connecting said bars with said door to prevent downward movement of said bars until said door is closed, and a pivoted member connected with said bars and adapted to rest upon the towel web which may be stretched from said delivering means to said towel roll, said pivoted member having a downward pull on said bars and automatically moving said supports out of the path of said towel roll to allow it to engage said winding means only when a predetermined length of towel web has been delivered.

6. A clean towel delivering means, a soiled towel take-up mechanism, and means including a tilting device in engagement with the towel web whereby said take-up mechanism is prevented from operatively engaging the towel and becoming operative to gather up the soiled towel until a loop of predetermined length is formed

- between said delivering means and said take-up mechanism.
7. A towel delivering means and a locking device therefor, adapted to be released to allow successive wiping lengths of towel to be delivered, a soiled towel winding mechanism adapted to wind up a corresponding length of soiled towel as the clean towel is delivered, and means made operative by the gradual lengthening of the towel loop to allow operative engagement of said winding mechanism with the towel whereby the winding of the soiled towel is permitted only when a loop of predetermined length has been formed between said delivering means and said winding mechanism.
8. In a towel cabinet, a clean towel delivering means, a frictional take-up roll for the soiled towel, a roll whereon the soiled towel is wound by contact with said take-up roll, tilting plates whereon said towel roll is supported in its non-working position out of contact with said take-up roll, and means whereby said plates will be actuated to allow said towel roll to move into contact with said friction roll when a predetermined length of towel loop for the user has been formed.
9. In a towel cabinet, means for delivering the clean towel, a roll for the soiled towel, and means to wind up the towel thereon, means normally preventing the engagement of said towel roll with said winding means, a pivoted yoke under which the web of towel may be passed to said towel roll, and mechanism connected with said yoke whereby when it has moved to a predetermined point said towel roll will be released to contact with said winding means.
10. In a towel cabinet means for delivering a supply of clean towel, means for winding up the soiled towel synchronously with the delivery of the clean towel, a soiled towel winding roll adapted to be engaged and revolved by said winding means, a pivoted member adapted to engage the loop of towel which may be stretched from the towel delivering means to said soiled towel roll, sliding bars pivotally connected with said loop engaging means, and mechanism pivotally connected with said bars, whereby said soiled towel roll is supported in a non-working position out of engagement with said towel winding means but is automatically released upon a predetermined movement of said loop engaging member and the formation of a loop of predetermined length between said towel delivering and winding means.
11. In a towel cabinet, a clean towel delivering means, a towel winding means and a roll whereon the soiled towel is wound, guides for said roll, plates having a vertical movement adapted to support said roll in the upper portions of said guides and prevent it temporarily from contacting with said winding means, vertically sliding bars pivotally connected with said plates, said guides being formed to allow said roll to slide past said plates when they are moved downward and a pivoted member adapted to contact with a towel web which may be stretched from said delivering means to said towel roll, said pivoted member being connected to said bars to exert a downward pull thereon thereby withdrawing said plates from the path of said towel roll and allowing it to drop into frictional contact with said winding means when a predetermined length of towel web has been delivered.
12. In a towel cabinet, means for delivering the clean towel, a soiled towel roll and means to wind the towel thereon, pivoted supports where-
- on the towel roll is seated and temporarily held thereby from contact with said winding means, sliding bars pivotally connected with said supports, a yoke connected with said bars and under which yoke a web of towel may be stretched to said towel roll, the yoke in its raised position being supported by the towel web and falling by gravity with the delivery of the clean towel, downward movement of said yoke releasing said towel roll to contact with said winding means.
13. In a towel cabinet, a clean towel delivering means, a soiled towel winding means, and a towel roll for the soiled towel, guides wherein said towel roll is slideable, said guides having enlarged middle portions, means normally supporting said towel roll above said enlarged portions and means controlled by the length of the towel loop between said delivering and winding means for moving said towel roll supports adjacent the enlarged portions of said guides whereby said towel roll will automatically become disengaged from said supports and move into contact with said winding means.
14. In a towel cabinet, means for delivering a supply of clean towel, a take-up roll, a towel roll adapted for contact with said take-up roll to be revolved thereby, a cabinet having an opening through which a loop of clean towel may be stretched to said towel roll, a fixed yoke member below said opening in position to contact with the towel loop, a pivoted yoke member adjacent said fixed member and adapted to rest on the towel loop and exert a downward pull thereon, and mechanism controlled by the movement of said pivoted yoke to permit the engagement of said towel roll with said take-up roll only when a predetermined length of loop has been formed between said delivering means and said towel roll.
15. In a towel cabinet, a carrier for a clean towel supply, a frame removably mounted above said carrier, towel delivering and take-up means mounted in said frame, a soiled towel roll movable in guides in said frame above said take-up means, means in the rear of said frame for supporting said soiled towel roll in a non-working position in the upper portion of said guides, means controlled by the length of the towel loop which may be formed between said delivering and take-up means for actuating said supporting means to release said towel roll and allow it to contact with said take-up means, the relative position of said supporting means and said frame being such that when said frame is inserted into the cabinet said supporting means will be in position to move across said guides and support said towel roll until said delivering means has dispensed a predetermined length of towel.
16. In a towel cabinet, means for delivering a supply of clean towel, a take-up roll, a soiled towel roll actuated by contact with said take-up roll to wind the soiled towel and guides for said soiled towel roll, wherein said roll is slideable toward and from said take-up roll, pivoted latches adapted to extend across said guides and support said towel roll therein out of contact with said take-up roll, links having a sliding connection with said latches and means connected with said links and adapted to actuate them to move said latches to a release position upon the delivery of a predetermined length of clean towel.
17. In a towel cabinet, means for delivering a supply of clean towel, a soiled towel take up, means whereto a web of towel may be stretched to form a loop, a fixed member positioned to

engage the loop and press it forwardly in the cabinet to increase the length of the loop, and a tilting member adapted to bear on the loop initially above said fixed member and swing down 5 past said fixed member and exert a downward and backward pull thereon against the pressure of said fixed member.

18. In a towel cabinet, means for delivering a supply of clean towel, a soiled towel take up 10 means whereto a web of towel may be stretched to form a loop, a fixed member positioned to engage the loop and press it forwardly in the cabinet, a tilting member adapted to bear on the loop and exert a downward and backward 15 pull thereon against the pressure of said fixed member, and mechanism controlled by the movement of said tilting member whereby said take-up means is rendered operative to wind up the soiled towel.

19. In a towel cabinet, means for dispensing a supply of clean towel, means to normally operate simultaneously with said dispensing means to wind up the soiled towel, a usable length or loop 25 of towel being drawn out preparatory to the use of the cabinet, means to engage the towel loop and movable as the length of the loop increases and mechanism made operative by said movable means to render said winding means effective at a predetermined point in the formation of 30 the towel loop to wind up the soiled towel.

20. In a towel cabinet, means for dispensing a supply of clean towel, means to normally operate simultaneously with said dispensing means to wind up the soiled towel, a usable length or 35 loop of towel being drawn out preparatory to the use of the cabinet, means to engage the towel loop and movable by gravity as the length of the loop increases, and mechanism made operative by said movable means to render said winding means effective at a predetermined point in the formation of the towel loop to wind up the 40 soiled towel.

21. In a towel cabinet, means for dispensing a supply of clean towel, a soiled towel take-up 45 means driven by said dispensing means, means normally supported by the towel loop, and mechanism normally permitting operation of said take-up means but preventing the take up of the soiled towel and connected with said loop 50 supported means whereby when a loop of predetermined length has been formed said take-up means will automatically become operative to take up the soiled towel.

22. A towel cabinet having clean towel delivery means and soiled towel take-up means, the toweling passing from the supply to delivery 55

means and providing a loop therein for convenient use of a user, measuring means between the clean towel supply and the take-up mechanism for the soiled towel for securing a proper length for said loop and means attached to the measuring means to disable said take-up means until a proper length loop is secured.

23. In a towel cabinet a clean towel supply, a clean towel feed, a soiled towel take-up mechanism, a measuring device to secure a proper length in the towel loop, said measuring device having connections with the soiled towel take-up to disable said take-up mechanism while leaving the delivery mechanism free to operate until a predetermined length of loop has been secured, said measuring mechanism being operative automatically to enable the take-up mechanism to operate when a predetermined length of loop is secured.

24. A towel cabinet having a door and a clean towel delivery mechanism, a soiled towel take-up mechanism, a towel loop measuring mechanism and means connected with said door to disable the soiled towel take-up mechanism and to maintain the same disabled until a predetermined length of towel has been secured in the towel loop and to automatically render operative the take-up mechanism when the predetermined length of loop is secured.

25. A towel cabinet comprising a clean towel delivery mechanism and a soiled towel take-up mechanism, a bar for securing a predetermined loop in the towel between the delivery and take up mechanism and means between the bar and take-up mechanism for disabling the latter until a predetermined length of loop has been secured and then to automatically enable the take-up mechanism to take up as much of the toweling as is delivered from the delivery mechanism.

26. A towel cabinet having therein means for indicating a proper length of towel loop, soiled towel take-up friction rolls and connections between the rolls and said means for separating the rolls until the loop of toweling is sufficiently long.

27. A towel cabinet having therein a towel delivery mechanism, a towel roll for winding up the soiled towel simultaneously with its delivery, a take-up roll normally in frictional contact with the towel roll, means to prevent contact between the towel roll and the take-up roll until a predetermined length of clean towel has been delivered to form a loop, said means further including loop measuring means, to automatically disable said preventing means when the loop reaches a predetermined length.
